UNITED STATES PATENT OFFICE.

CLYDE S. WHIPPLE, OF PORTLAND, INDIANA, ASSIGNOR TO A. H. HEISEY & CO., INC.,
A CORPORATION OF WEST VIRGINIA.

DESIGN FOR A GLASS VESSEL.

No. 39,432.

Specification for Design.

Patented July 21, 1908.

Application filed May 9, 1898. Serial No. 431,991. Term of patent 7 years.

To all whom it may concern:

Be it known that I, CLYDE S. WHIPPLE, a citizen of the United States, residing at Portland, in the county of Jay and State of Indiana, have invented a new, original, and ornamental Design for a Glass Vessel, of which the following is a specification, reference being had to the accompanying drawing, forming part thereof.

The figure is an elevation of a glass vessel with its upper portion in dotted lines.

I claim:

The ornamental design for a glass vessel as shown.

CLYDE S. WHIPPLE.
